[57] CLAIM

The ornamental design for a straight peg hook, as shown and described.

DESCRIPTION

FIG. 1 is a front perspective view of a straight peg hook embodying my new design;
FIG. 2 is a front elevational view thereof;
FIG. 3 is a rear elevational view thereof;
FIG. 4 is a side elevational view thereof. The side opposite to that depicted in FIG. 4 is identical in appearance;
FIG. 5 is a top plan view thereof;
FIG. 6 is a bottom plan view thereof.

FIG.1

FIG.2

FIG. 3

FIG. 4

FIG. 5

FIG. 6
